SHOCKPROOF X-RAY UNIT

Charles Morse Slack, Glen Ridge, N. J., assignor,
by mesne assignments, to Westinghouse Electric
and Manufacturing Company, East Pittsburgh,
Pa., a corporation of Pennsylvania

Application October 31, 1934, Serial No. 750,760

3 Claims. (Cl. 250—34)

My invention relates to X-ray apparatus and has particular reference to shockproof X-ray apparatus wherein the danger of accidental shocks resulting to a patient or operator are entirely eliminated.

In the prior art the most common type of such apparatus is that of the so-called oil immersed type wherein the X-ray tube and the high tension transformer are immersed in a cooling and insulating material and encased in a metallic casing. However, a unit of this type has several disadvantageous features among which are its weight, which makes it very unwieldy to manipulate and as the tube is immersed in oil the latter acts as a filter for the X-rays emanating from the tube.

A further type of shockproof unit which obviates the objectionable features inherent in the oil immersed type is that known as the cable connected unit. This latter type consists of a metallic housing for the X-ray tube and the energy for operating the tube is supplied from a suitable source through grounded metallic sheathed cables. The cables are suitably secured to the metallic casing through the intermediary of appropriate connecting bushings to effectively ground the metallic housing. The midpoint of the high tension transformer, which latter normally is employed for the source of energy, is usually grounded thus requiring insulation between the electrode terminals of the tube and the metallic casing sufficient to prevent spark-over at a voltage equal to one-half the maximum voltage of the source.

Because the tube in this cable connected shock-proof unit operates in air it is of larger size for the same applied voltage as when operating in oil. However, the tube size may be reduced somewhat below that normally required for a tube operating in air by the provision of suitable insulation between the tube terminals and the grounded metallic casing.

Heretofore it has been customary to provide blocks or sleeves of insulating material between the cable bushings and the tube terminals which are in turn provided with suitable terminals for connecting the respective conductors of the cables to the electrode terminals of the tube. This construction is not only costly to manufacture and assemble but in addition forms numerous leakage paths between the high tension carrying parts and grounded metallic casing where corona very readily forms during operation of the tube as well as frequent spark-over due to deterioration of the insulating material by the corona effect.

It is accordingly an object of my present inven-

tion to provide a shockproof X-ray unit wherein the X-ray tube is of a foreshortened length than normally required for a tube operating in air at the same applied voltage and the electrical energy for energizing the same is supplied through grounded metallic sheathed cables which enter the ray proof housing and are so connected to the terminals of the X-ray tube as to reduce the spacing normally required between the tube terminals and the grounded casing.

Another object of my present invention is the provision of a cable connected shockproof unit wherein the high tension carrying cables are so connected to the metallic ray-proof housing as to effectively ground the same and are connected to the terminals of the tube in such manner as to conceal all high tension carrying parts whereby sparkover and the formation of corona is eliminated resulting in the utilization of an X-ray tube of smaller dimensions than that normally required for a tube operating in air at the same applied voltage.

Another object of my present invention is the provision of a shockproof X-ray unit wherein the high potential energy for the tube is supplied by grounded metallic sheathed cables connected to the ray-proof metallic housing and the X-ray tube terminals in such manner as to ground the housing and form a support for the tube as well as sufficiently insulate the tube terminals so that the actual air gap spacing between the latter and the grounded housing may be reduced resulting in the utilization of a tube of foreshortened length for the same applied voltage as normally required when operating in air.

Another object of my present invention is the provision of a shock-proof X-ray unit wherein the overall length of the tube is considerably reduced below that normally required for a tube operating in air at the same applied voltage and provided with reentrant stems having the electrode terminals recessed therein and the high tension cables for supplying the energy for the tube are connected directly to the recessed electrode terminals to form the requisite insulation to prevent spark-over and the formation of corona between these terminals and the surrounding grounded ray-proof housing.

A further object of my present invention is the provision of an X-ray tube of foreshortened length provided with reentrant stems and having its respective electrode terminals recessed therein a sufficient distance to prevent spark-over therebetween at the maximum operating voltage of the tube.

Still further objects of my present invention will become obvious to those skilled in the art by reference to the accompanying drawings wherein:

- 5 Figure 1 is a side view, partly broken away, of a shockproof X-ray unit constructed in accordance with my present invention.
- Fig. 2 is a sectional view taken on the line II—II of Fig. 1.
- 10 Fig. 3 is a sectional view taken on the line III—III of Fig. 1.
- Fig. 4 is a sectional view taken on the line IV—IV of Fig. 1.
- Fig. 5 is a side view in cross section and on an enlarged scale of the unit shown in Fig. 1, and
- 15 Fig. 6 is a sectional fragmentary view on a still larger scale of the unit as shown in Fig. 5.
- Referring now to the drawings in detail I have shown in Fig. 1 an X-ray tube comprising an elongated evacuated vitreous envelope 5 which is surrounded by a metallic or other suitable ray opaque housing 6 for preventing the egress of X-rays except through a window 7 provided in the housing. The envelope is provided with re-entrant stems 8 and 9 extending well into the envelope, as can be more readily seen in Fig. 5, with the innermost portion of the stem 8 being formed into a press 10 through which a pair of conductors 11 pass to the cathode electrode shown generally at 12. This latter electrode comprises the usual filament 13 which is recessed within a focusing cup or shield 14, in turn fitting over the press portion 10 of the reentrant stem 8, and secured in place by means of a metallic ring or the like 15. An insulated disc 16 is suitably secured to the inner periphery of the reentrant stem 8 at the inner extremity thereof and is provided with a pair of recessed metallic sleeves 17 and 18 which are connected to the filament 13 by the conductors 11 passing through the press and thus constitutes the cathode terminal for the tube.
- An anode electrode 19 formed of a material of good electrical and thermal conductivity, such as copper or the like, and provided with the usual target 20 of refractory metal, is sealed by a feather edged copper annulus 21 to the reentrant stem portion 9 of the envelope 5. A vitreous glass sleeve 22 fused to the envelope is disposed internally thereof and extends longitudinally from well in back of the point of seal of the anode and the envelope to considerably beyond the press 10 formed in the reentrant stem 8. This sleeve is provided with constrictions 23 adjacent the anode and cathode but as the construction and operation of the same forms the basis of my copending application Serial No. 750,633, filed October 30, 1934, and forms no part per se of my present invention further detailed description herein is deemed unnecessary.
- 60 The anode 19 is provided with a longitudinal recess 24 (Fig. 6) threaded at the outer end adjacent the reentrant stem 9 and is arranged to be engaged by a metallic member 25 provided with a recess 26 which together form an anode terminal similar to the cathode terminal comprising the disc 16 with its recessed sleeves 17 and 18. In order to circulate a cooling and insulating medium through the anode, such for example as oil, to cool the same during operation of the tube the member 25 is further provided with a metallic conduit 27 threadedly engaging the same and extending well into the recess 24, and this conduit registers with a radially extending passageway or bore 28 formed therein and made fluid tight by means of a plug 29.

A suitable fitting in the form of an elbow of insulating material 30 also threadedly engages the member 25 and forms a passageway communicating with the bore 28. An inlet conduit 31 also of suitable insulating material extends from an appropriate reservoir (not shown) which in turn engages the elbow thus forming a continuous inlet passage from the reservoir to the interior of the anode with the insulation characteristic of the oil being augmented by the insulated elbow 30 and the conduit 31 so that the potential applied to the anode will not be transmitted to other parts of the unit by the cooling system.

The conduit 27 is of slightly less diameter than the recess 24 provided in the member 25 for a portion of its length and thus forms an annular passageway 32 communicating with the interior of the hollow anode recess 24. An angularly disposed passageway 33 in the member 25 communicates with the annular passage 32 and an elbow 34, similar to the elbow 30, threadedly engages the member 25 concentric with the passageway 33, said elbow being in turn engaged by an insulated return or outlet conduit 35 leading back to the reservoir.

Accordingly during operation of the tube the cooling fluid flows from the reservoir through the inlet conduit 31, elbow 30, passageway 28 and conduit 27 to the interior of the anode immediately in back of the target. The cool fluid after striking the heated parts of the anode then flows through the passageways 24, 32, and 33, respectively, and thence by means of the elbow 34 and outlet conduit 35 back to the reservoir. Moreover, due to the insulating material itself and the utilization of insulated conduits no potential stress is impressed between any other portions of the apparatus and the circulatory cooling system.

The respective ends of the envelope of the tube 40 have insulated caps 36 and 37 secured thereto in any suitable manner, such for example as cement 38. In order to support the tube, as well as supply high potential energy thereto from a suitable source, such as a high voltage transformer (not shown) having the midpoint of its secondary winding grounded, a pair of grounded metallic sheathed cables 39 and 40 extend from the source to the tube. These cables have the metallic sheathing removed therefrom a distance 50 corresponding to that from the outside surface of the respective end caps 36 and 37 and the cathode and anode terminals which latter are, as before stated, disposed at the innermost extremities of the respective reentrant stems 8 and 9. A sleeve of insulating material 41 snugly fits the unsheathed portions of the respective cables and accordingly forms an integral part thereof. The sleeve 41 forming a part of the cable 39 is provided with a pair of pins 42 slidably engaging the recessed sleeves 17 and 18 of the cathode terminal with these pins being connected to the conductors of the cable 39 for the purpose of supplying cathode heating current as well as one side of the high potential energy to the cathode, 65 and the cable 39 is held in position by a flange portion 43 of the sleeve 41 which engages the end cap 36 in any suitable manner, such as by set screws 44, thus supporting one end of the tube 5 directly upon the cable 39.

Similarly the insulating sleeve 41, which forms an integral part of the cable 40 is likewise provided with a pin 45, electrically connected to the conductor in the cable 40, said pin slidably engaging the recess 26 provided in the member 75

25 and constituting the anode terminal. This cable 40 supports the anode end of the tube in the same manner as the cathode end is supported by the cable 39, namely, by having the flange 5 portion of its insulating sleeve 41 secured to the end cap 37.

Accordingly the cables 39 and 40 extend directly into the reentrant stems 8 and 9, respectively, and the conductors of these cables are not only connected directly to the electrode terminals disposed interiorly of these reentrant stems, but the tube itself is supported directly by the cables due to their integral sleeves 41 being connected to the respective end caps 36 and 37.

15 Inasmuch as these grounded high tension cables directly enter the reentrant stems and are connected to the respective recessed electrode terminals they not only conceal all high tension carrying parts but in addition form sufficient 20 insulation enabling the spacing between the grounded sheathing of the cables 39 and 40 as well as the metallic casing 6 to be materially reduced for a tube normally operating in air at the same applied voltage. Moreover, a single 25 leakage path is formed along which the current would have to travel to cause a spark-over, namely, between the respective electrode terminals along the integral cable sleeves 41 to the grounded sheathing or casing but, despite the fact that the 30 actual air gap spacing therebetween is materially reduced as just stated, this path is more than sufficient to prevent spark-over or the formation of corona tending to cause deterioration of the insulation. By enabling the spacing between all high tension carrying parts and ground to be materially reduced it naturally follows that the overall size of the entire unit is likewise reduced thus forming a more compact unit which may be manipulated about a patient with greater 35 facility and is more economical to manufacture.

40 The metallic housing 6 surrounds the tube 5 and in order to render it ray pervious except at the window 1 the same may be provided with a layer of metal 46, of high atomic weight such as 45 lead or the like. Each end of the casing is supported by the respective end caps 36 and 37 of the tube. For the purpose of completing a metallic connection for the metallic housing to the grounded metallic sheathing of the cables 39 and 50 40, a metallic collar 47 threadedly engages each end of the housing and is provided with a portion 48 having a plurality of slots 49 extending longitudinally to form a good frictional contact with the metallic sheathing of the respective 55 cables and yet allow a slight flexibility thereof.

55 It thus becomes obvious to those skilled in the art that I have provided a shockproof X-ray unit wherein the possibility of accidental shocks resulting to a patient or operator are entirely eliminated. The high potential energy for the tube is supplied through grounded metallic sheathed cables which are directly connected to recessed electrode terminals of the tube in such a manner that not only are all high tension carrying parts concealed but, in addition the insulation formed by the cables themselves is such as to reduce the actual air gap spacing between the electrode terminals and grounded parts of the apparatus. This results in the utilization of an X-ray tube of foreshortened length than that normally required for a tube operating in air at the same applied voltage and forms a compact shockproof and ray-proof unit of light weight thus enhancing the facility of manipulation about a patient for examination and treatment.

Although I have shown and described one specific embodiment of my invention I do not desire to be limited thereto as various other modifications of the same may be made without departing from the spirit and scope of the appended claims. 5

What is claimed:

1. A shockproof X-ray apparatus comprising a metallic housing, an X-ray tube disposed in said housing having an envelope of shorter length than that normally required for a tube operating 10 in air at the same applied voltage and provided with oppositely disposed reentrant stems extending a substantial distance longitudinally of said envelope, electrode terminals disposed at the innermost extremity of said reentrant stems, and 15 means for supporting said tube and for supplying electrical energy thereto comprising grounded metallic sheathed cables having the metallic sheathing thereof connected to said metallic housing and provided with an unsheathed portion, 20 an insulated sleeve snugly fitting the unsheathed portion of said cables and extending directly into said reentrant stems to form a single leakage path and to increase the air-gap spacing between said electrode terminals and all 25 grounded metallic parts to prevent the formation of corona during operation of said tube, said insulated sleeve being connected to said X-ray tube and said housing to form a support therefor, and said insulated sleeves having terminals connected 30 to said cables and slidably engaging the electrode terminals disposed at the innermost extremity of said reentrant stems.

2. A shockproof X-ray apparatus comprising an X-ray tube having an envelope of shorter length 35 than that normally required for a tube operating in air at the same applied voltage and provided with oppositely disposed hollow reentrant stems extending a substantial distance longitudinally of said envelope, electrode terminals disposed at 40 the innermost extremity of said reentrant stems, a metallic X-ray opaque housing supported by said tube and spaced relative to said electrode terminals a distance which is normally insufficient to prevent spark-over or the formation of 45 corona therebetween during operation of said tube, grounded metallic sheathed cables for supplying electrical energy to said X-ray tube and for supporting said tube and housing as a unit, said cables having the metallic sheathing thereof 50 connected to said housing to ground the latter and provided with an unsheathed portion, an insulating sleeve snugly fitting the unsheathed portion of said cables and extending directly into said reentrant stems to form a single leakage 55 path and to increase the air-gap spacing between said electrode terminals and all grounded metallic parts to prevent the formation of corona during operation of said tube, said insulating sleeve being provided with a flange portion secured to said tube and contacting said housing whereby said X-ray tube and housing are supported as a unit by said cables, and said insulated sleeves having terminals connected to said cables and slidably engaging the electrode terminals 60 disposed at the innermost extremity of said reentrant stems.

3. A shockproof X-ray apparatus comprising an X-ray tube having an envelope of shorter length than that normally required for a tube 70 operating in air at the same applied voltage and provided with oppositely disposed hollow cylindrical reentrant stems extending a substantial distance longitudinally of said envelope, an X-ray opaque housing surrounding said X-ray tube and 75

in contact with a portion of said tube to fix the position thereof within said housing and provided with an X-ray pervious window in said housing in alignment with the ray projecting portion of said X-ray tube, electrode terminals disposed at the innermost extremity of said reentrant stems and spaced from said housing a distance normally insufficient to prevent spark-over therebetween at the operating voltage of said tube, grounded metallic sheathed cables for supplying electrical energy to said X-ray tube and having an unsheathed portion, a metallic flange carried by the metallic sheathed portion of said cables and connected to said housing to ground the latter, an insulating sleeve snugly fitting the unsheathed

portion of said cables and extending directly into said reentrant stems to form a single leakage path and to increase the air-gap spacing between said electrode terminals and all grounded metallic parts to prevent spark-over or the formation of corona during operation of said tube, said insulating sleeve being provided with a flange secured to said tube to support said housing and tube as a unit upon said cables, and said insulated sleeves having terminals connected to said cables and slidably engaging the electrode terminals disposed at the innermost extremity of said reentrant stems.

CHARLES MORSE SLACK. 15
